US00D790494S

(12) **United States Design Patent** (10) **Patent No.:** **US D790,494 S**
(45) **Date of Patent:** **** Jun. 27, 2017**

(54) **CELLULAR PHONE**

(71) Applicant: **LG ELECTRONICS INC.**, Seoul (KR)

(72) Inventors: **Hophil Lee**, Seoul (KR); **Hyonl Kim**, Seoul (KR); **Jihoon Shin**, Seoul (KR)

(73) Assignee: **LG Electronics Inc.**, Seoul (KR)

(**) Term: **14 Years**

(21) Appl. No.: **29/512,252**

(22) Filed: **Dec. 17, 2014**

(30) **Foreign Application Priority Data**

Jun. 25, 2014 (KR) 30-2014-0031212

(51) **LOC (10) Cl.** **14-03**

(52) **U.S. Cl.**

USPC ..... **D14/138 G**

(58) **Field of Classification Search**

USPC ..... D14/138 G, 138 AD, 341, 138 R, 496, D14/203.1, 203.3, 203.5, 203.7, 144, 250; D21/517, 329

CPC .. G06F 1/1626; H04M 1/0266; H04M 1/0202

See application file for complete search history.

(57) **CLAIM**

The ornamental design for a cellular phone, as shown and described.

DESCRIPTION

FIG. 1 is a front, right side, perspective view of a cellular phone showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines that are immediately adjacent to the claim, encompassing unshaded regions, represent the bounds of the claim, while all other broken lines are directed to environment; the broken lines form no part of the claimed design.

1 Claim, 6 Drawing Sheets
